UNITED STATES PATENT OFFICE.

MYRON M. KINLEY, OF TULSA, OKLAHOMA.

APPARATUS FOR PLUGGING WELLS.

Application filed June 4, 1926. Serial No. 113,712.

My invention relates to a method of and apparatus for plugging wells and has for its principal object to shut off the flow of water to a well from which production is to be sought from sands above the water flowing stratum.

In some instances wells which have been drilled through oil bearing sands into water strata or into oil strata which have gone to water after producing periods, are plugged to shut off the water from the lower levels and permit production from the upper sands.

As such plugging must be effected at a depth of from a few hundred to several thousand feet, and within a hole of but a few inches in diameter, it is difficult if not impossible to accurately determine the exact point where the plug should be located, and to then locate and seal the plug in the well.

It is, therefore, one of the objects of my invention to provide a plug which may be easily and accurately located in a well and which, when located, may be sealed to the wall of the well in a manner to effectively prevent flow of water to the portion of the well above the plug.

It is also an object of my invention to provide a method and apparatus which will not require reinstallation of heavy reeling equipment for its operation but which may be employed with a portable reel immediately upon removal of the rods and pump.

In accomplishing these objects I employ the method and apparatus hereinafter described by reference to the accompanying drawings, wherein a preferred form of structure is illustrated and wherein:

Fig. 1 is a vertical section of an oil well within which a plugging apparatus constructed according to my invention is being lowered;

Fig. 2 is a vertical section of the lower, uncased portion of a well, showing water and gas bearing sands, and showing the plugging apparatus broken away for better illustration.

Fig. 3 is a view of the well as it appears when plugged.

Referring more in detail to the drawings:

1 designates a well hole, which has been drilled through earth 2 (Fig. 1) and oil bearing sand 3, into water sand 4 (Figs. 2 and 3), the upper portion of the well being provided with the usual casing 5. 6 designates a container, preferably of the greatest

possible diameter that will permit it to pass through the well hole without stoppage, so that the least possible expansion of the container will carry it into contact with the 60 wall of the well, and of the lightest practicable gauge of sheet metal, so that the wall of the container may be completely disrupted under the conditions presently stated.

Located within and forming the bottom 65 of the container 6 is a plug 7 of expansible and non-corrodible material, preferably lead, having an upwardly-opening chamber or pocket 8 of a size to contain sufficient explosive for expanding the plug against the 70 wall and disrupting the container to sever it so that the upper portion may be removed from the well. The chamber or pocket 8 is filled with explosive material 9 and embedded in said material is a fulminating cap 10. Connected with the cap 10 is a circuit wire 11, the mate 12 of which is grounded on the container 6; the two wires being extended through the container as a cord 13, which is attached to the bale 14 80 and serves as a cable for letting in the container. The cord 13 may be run over the usual pulleys and connected to the usual winding drums (not shown) and the circuit wires may be connected with the usual battery through the usual switch, none of which latter parts are illustrated, as they may be of forms employed in ordinary practice, and their detail structures form no part of the present invention.

Filling the container about the plug 7 is a quantity of cement 15, preferably in neat mixture form, and suspended from the container, preferably in a burlap bag 16 and by a bale 17 partly embedded in the lead plug, 95 is a mass of fibrous packing material 18, preferably oakum.

Assuming that the point for location of the plug has been ascertained from the log of the well, and that the apparatus has been 100 constructed and assembled as described, plugging of the well is effected as follows:

The container is let into the well to the proper point and held suspended while the charge of explosive is fulminated by closing the battery circuit through the switch. When the charge is exploded, it expands the plug into sealing contact with the wall of the well to hold the plug firmly in and seal the hole.

Explosion of the charge disrupts the container about the upper edge of the plug,

blowing the upper portions of the container up into the well hole and freeing the cement so that the latter flows out into the well and settles onto the plug in a mass which, when set, forms a seal supplementing that of the lead plug in preventing flow of water from the water sands into the well.

With the plug set as described, accumulation of water pressure beneath the plug forces the oakum up into crevices about the plug to seal any opening that may be occasioned by irregularities in the surface of the plug or wall of the well.

The upper portion of the container may be removed from the well with the letting in and fulminating cord to leave the well free for the installation of pumps.

What I claim and desire to secure by Letters Patent is:

1. Apparatus for plugging wells comprising a rupturable container, a plug of expandable material in the lower portion of the container providing an upper space for sealing material and having a chamber for containing a charge of explosive, and fulminating means comprising a cap located in said chamber.

2. In apparatus for plugging wells, a container, a plug of expandable material at the bottom of the container having a chamber for containing a charge of explosive, the

container extending beyond the plug to retain a quantity of sealing material, and means for fulminating a charge of explosive in the plug chamber.

3. In an apparatus for plugging wells, a container, a plug of expandable material at the bottom of the container having a chamber for containing a charge of explosive, the container extending beyond the plug to retain a quantity of sealing material, a fulminating cap in the explosive chamber, and means for letting in the container comprising wires having circuit connection with said cap.

4. In an apparatus for plugging wells, a container, a plug of expandable material at the bottom of the container having a chamber for containing a charge of explosive, the container extending beyond the plug to retain a quantity of sealing material, and a mass of fibrous material suspended from said plug.

5. A cartridge for the purpose set forth comprising a container, an expandable plug located in the container and having a chamber for an explosive, an explosive in said chamber, means for fulminating the explosive, and sealing material in the container above the plug.

In testimony whereof I affix my signature.
MYRON M. KINLEY.
